(57) **CLAIM**

The ornamental design for a golf shoe sole, as shown and described.

DESCRIPTION

FIG. 1 is a bottom view of a golf shoe sole showing our new design;

FIG. 2 is a left side elevational view thereof;

FIG. 3 is a right side elevational view thereof;

FIG. 4 is a rear elevational view thereof; and,

FIG. 5 is a front elevational view thereof.

The circular portions removed from FIG. 1 are intended to show potential cleat locations and are not considered part of the invention.
